(57) **CLAIM**

The ornamental design for a passenger information module with on demand channel screen of graphical user interface, as shown and described.

DESCRIPTION

FIG. 1 is a perspective view of the passenger information module in which the on demand channel screen of the claimed design is embodied; and,

FIG. 2 is a front view of the on demand channel screen of the claimed design.

The dashed lines in FIG. 1 show the environment, and form no part of the claimed design.

The dashed lines in FIG. 2 illustrate portions of the on demand channel screen which form no part of the claimed design.

1 Claim, 2 Drawing Sheets

UNITED STATES PATENT AND TRADEMARK OFFICE
CERTIFICATE OF CORRECTION

PATENT NO. : D698,803 S
APPLICATION NO. : 29/449789
DATED : February 4, 2014
INVENTOR(S) : Davis

Page 1 of 1

It is certified that error appears in the above-identified patent and that said Letters Patent is hereby corrected as shown below:

On the Title Page, Item (71), under "Applicant", in Column 1, Line 1, delete "Techologies," and insert -- Technologies, --, therefor.

Signed and Sealed this
Twentieth Day of May, 2014

Michelle K. Lee
Deputy Director of the United States Patent and Trademark Office
